ON LINE 3-3, FIG. 2

UNITED STATES PATENT OFFICE.

WILLIAM J. BUSSINGER, OF PHILADELPHIA, PENNSYLVANIA, ASSIGNOR TO LOUIS J. McGRATH, WILLIAM J. BUSSINGER, MARCUS A. SCHCALES, AND THE ESTATE OF THOMAS DEVLIN, DECEASED, A COPARTNERSHIP TRADING AS NATIONAL SPECIALTY MANUFACTURING COMPANY, OF PHILADELPHIA, PENNSYLVANIA.

POTATO SLICER.

Application filed August 11, 1922. Serial No. 581,080.

To all whom it may concern:

Be it known that I, WILLIAM J. BUSSINGER, a citizen of the United States, residing in the city and county of Philadelphia, 5 State of Pennsylvania, have invented a new and useful Potato Slicer, of which the following is a specification.

My invention relates to a novel construction of a vegetable or potato slicing machine, 10 which is especially adapted for expeditiously in a single operation, slicing vegetables as potatoes into the shape of elongated rectangles, which when prepared for the table are commonly known as French fried potatoes.

15 To the above ends, my invention consists of a novel construction of a frame-work or body provided with a horizontally disposed trough, in which the potatoes or other vegetables to be sliced are received and are actuated or impelled by a longitudinally movable plunger, towards the slicing devices, which are composed of sharpened blades 20 rectangularly arranged in a detachable frame.

It further consists of a novel construction 25 of racks and pinions on either side of the trough, in which the potato or other vegetable to be sliced is received, in conjunction with actuating mechanism common thereto and to the movable plunger, by which the 30 slicing operations are effected.

It further consists in a novel construction of movable head having a plunger provided 35 with a plurality of rectangular tapering projections arranged in rows, said plunger being capable of being readily disengaged from the supporting head, so that it can be washed or cleaned, according to requirements.

If further consists of a novel manner of 40 detachably supporting and clamping in position the frame containing the rectangularly arranged cutting blades, whereby the potato or other vegetable is sliced.

It further consists of a novel manner of 45 casting and assembling the various elements, composing the body or frame-work of the slicer, the trough, actuating mechanism, and their adjuncts, whereby the manufacture and assembling of the device can be effected with great economy.

50 It further consists of other novel features

of construction, all as will be hereinafter fully set forth.

For the purpose of illustrating my invention, I have shown in the accompanying drawings forms thereof which are at present 55 preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of 65 a potato or other vegetable slicer embodying my invention.

Figure 2 represents a top plan view of Figure 1.

Figure 3 represents a section on line 3—3 70 Figure 2.

Figure 4 represents a section on line 4—4 75 Figure 2, showing the manner of supporting and clamping the slicing mechanism.

Figure 5 represents a section on line 5—5 80 Figure 4, showing the arrangement of the cutting blades.

Figure 6 represents on an enlarged scale a section on line 6—6 Figure 2, showing the manner of securing in position the plunger 80 with respect to its support and actuating head.

Similar numerals of reference indicate corresponding parts in the figures.

Referring to drawings:—

1 designates my novel construction of potato or other vegetable slicer, the same comprising a body or upright portion, composed of a pair of upright members 2 having the base 3 and the upper outwardly inclined terminal flanges 4, which engage the inclined walls 5, whereby a horizontally disposed trough is formed, in which the potato or other vegetable to be sliced is received, and propelled towards the slicing devices. 90

The inclined trough forming members 5 are each provided with the pair of outer lugs 6, against which are secured the racks 7 by means of the transverse bolts or other fastening devices 8, said bolts being screwed 100

into said lugs and it being apparent that the teeth on the upper portion of said racks are rigidly supported in parallelism and in horizontal alignment.

5 9 designates pinions, which are fast on the shaft 10, which is rotatably mounted in the ears 11 of the head 12, which is in the form of a vertical rectangular plate arranged so as to fit in the trough formed by the walls 5, 10 and having the lower longitudinal extension or guide member 13, which is movably mounted in the horizontal longitudinal opening or ways 14 formed at the upper portion of the uprights 2, said portion 13 15 having secured to the under side thereof the washers 15, whose outer peripheries engage the bottom edges 16 of the inclined sides 5, so that the head 12 and its plunger are prevented from vertical or upward movement, said washers being secured in position 20 by the screws 17. The foregoing constitutes a neat and readily assembled device for securing the head 12 and its adjuncts in position, and as will be understood from Figure 3, serves to retain the pinions 9 in engagement with their racks, at all times.

25 The head 12 is provided with a vertical slot 18 therein, which is engaged by the wing nut 19, the threaded portion of which engages the plunger 20. The plunger 20 is provided with a back wall 21, which carries a series of forwardly projecting tapering rectangular or pyramidal projections 22, which align with the square openings 23 formed between the sharpened blades 24 and 25, which are arranged at right angles in the rectangular frame 26, as will be understood from Figures 1 and 4. The frame 26 is supported in a V-shaped seat composed 30 of the upwardly diverging bottom walls 27, which are preferably cast upon the V-shaped walls 5 and meet at the bottom apex 28. To one of said walls is hinged at 29 the top clamping frame composed of the downwardly diverging walls 30, and the lower end 35 of one of said walls is provided with a slot 31, which is engaged by the threaded stem 32, which is pivotally mounted at 33 and engaged by a wing nut 34, it being apparent 40 that when said wing nut 34 is loosened and the threaded stem 32 dropped, the top clamping frame composed of the members 30 can be lifted into the position seen in dotted lines in Figure 4, whereupon the rectangular frame 26 carrying the blades 24 and 25 can be removed and washed or cleaned.

45 The pinions 9 are provided with guards 35, which have a central hole therethrough, through which passes the ends of the shaft 50 10. The crank handle 36 is secured to one end of the shaft 10 and the cotter pin 37 passing through the other end of said shaft retains the latter in assembled position with respect to the pinions and the guards 35, 65 it being apparent that the crank handle 36,

shaft 10 and pinions 35 rotate as a unit and that the engagement of the said pinions with the teeth of the racks 7 causes the head 12 and the plunger 20 to reciprocate to and from the cutting or slicing devices 24 and 25. 70

The slicer is clamped to a table, shelf or other support 39 by the clamp 38.

The operation is as follows:

75 The parts appearing as seen in Figure 1, the potato or other article to be sliced is placed in the trough formed between the inclined walls 5, between the plunger 20 and the slicing devices seen at the left of Figure 1. The handle 36 is then actuated, whereupon the potato is propelled towards the slicing devices, and the tapered rectangular projections, 22 entering the aligning squares 23 will force the potato through them, and the potato will be sliced into the form of elongated rectangles commonly known, when 85 fried as French fried potatoes. The plunger 20 is now in its extreme left hand position, and the members 22 have passed through the aligning squares 23. Upon turning the handle 36 into the position seen in Figure 1, the 90 other parts assume the position seen therein.

95 It will be apparent that the actuation of the handle 36 rotates the shaft 10 and pinions 9 as a unit and the engagement of said pinions with the stationary racks 7, effects the forward and backward movement of the plunger 20, and its adjuncts. For convenience of manufacture, I cast the inclined sides 5, the V-shaped walls 27 and the wall 40 seen in Figure 2, together, said wall 40 100 serving to limit the outward movement of the plunger by the contact of the portion 13 therewith.

105 The various elements of which my novel device is composed can be cheaply cast and assembled together without the employment of skilled labour, and a minimum amount of machining is required, as is evident.

110 While my invention is particularly adapted for slicing French fried potatoes, it can be used for other purposes as is evident.

Having thus described my invention, what I claim as new and desire to secure by Letters Patent is:—

115 1. In a vegetable slicer, a receptacle for the vegetable, a stationary slicing device composed of a plurality of openings bounded by cutting edges, a plunger having a plurality of aligning projecting members adapted to enter and pass through said 120 openings, and means for actuating said plunger, comprising a shaft extending transversely of said plunger, pinions on the ends of said shaft and a pair of stationary racks suitably supported and engaged by 125 said pinions and a handle for rotating said transverse shaft.

130 2. In a potato slicer, a body portion, a horizontally disposed trough therefor, racks arranged in parallelism at each side

of said trough, a head movable in said trough, ears projecting from said head, a shaft passing through said ears transversely of said trough, pinions fast on said shaft 5 and engaging said racks, a plunger carried by said head and having projections thereon, and slicing devices coacting with said projections.

3. In a vegetable slicer, a receptacle for 10 the vegetable, a detachable stationary slicing device composed of a plurality of openings bounded by cutting edges, a plunger detachable from its support and having a plurality of projecting members aligning 15 with and adapted to enter said openings, plunger actuating means comprising a shaft extending transversely of said plunger, a pinion on the end of said shaft, a stationary rack on the side of said receptacle engaged by said pinion, and means 20 for rotating said transverse shaft.

4. In a potato slicer, a trough, parallel aligning stationary racks on each side of 25 said trough, a longitudinal opening forming ways in the bottom of said trough, a head 30 slideable in said trough and having a bottom guide member engaging said ways, ears on said head, a shaft passing transversely through said ears, pinions fast on 35 said shaft and engaging said racks, a handle on said shaft for rotating the latter and said pinions, a plunger detachably secured to said head and having rectangular tapering 40 projections thereon, and slicing devices carried by said trough and coacting with the 45 projections on said plunger.

5. In a vegetable slicer, a receptacle for 40 the vegetable, a stationary slicing device composed of a plurality of openings bounded 45 by cutting edges, a plunger adapted to propel the vegetable towards said cutting edges, guiding devices below said plunger and movable in unison therewith, and contacting with the bottom of said receptacle 50 for guiding said plunger, a shaft extending transversely of said plunger and connected therewith, pinions on said shaft near the outer ends thereof, a pair of stationary parallel racks engaged by said pinions and 55 means for actuating said shaft and pinions in unison with respect to said racks.

6. In a potato slicer, a trough, racks on 55 the side of said trough, pinions engaging said racks, a shaft extending transversely to 60 said trough on which said pinions are inmounted, a head having ears in which said shaft is mounted, ways in the bottom of said trough, a bottom guide member carried by said head, guiding devices secured to the bottom of said guide member for causing 65 said pinions to engage said racks, a plunger

carried by said head, and slicing devices coacting with said plunger.

7. In a potato slicer, a body portion composed of a plurality of uprights, fastening devices for the bottom of said uprights, a trough secured to the upper portions of said uprights, said trough having ways at its bottom, and terminating at one end in a V-shaped frame, slicing devices clamped 70 within said frame, a plunger movable in said trough, and means for actuating said plunger, comprising a transverse shaft, pinions on the ends of said shaft and stationary parallel racks engaged by said pinions and 75 a handle for rotating the latter and said pinions in unison.

8. In a potato slicer, a body portion composed of a plurality of uprights, fastening devices for the bottom of said uprights, a 80 trough secured to the upper portions of said uprights, said trough having ways at its bottom, and terminating at one end in a V-shaped frame, slicing devices clamped within said frame, a head carrying a 85 plunger movable in said trough, means for actuating said head, comprising a transverse shaft, pinions on said shaft, stationary racks engaged by said pinions, a handle on said shaft for rotating the latter and said 90 pinions in unison, a guide member on the bottom of said head and movable in said ways, and a wall on the end of said trough opposite to said slicing devices for limiting the movement of said head and 95 plunger.

9. In a potato slicer, a body portion composed of a plurality of uprights, fastening devices for the bottom of said uprights, a trough secured to the upper portions 100 of said uprights, said trough having ways at its bottom, and terminating at one end in a V-shaped frame, slicing devices clamped within said frame, a head carrying a plunger movable in said trough, 105 means for actuating said head, comprising a transverse shaft, pinions on said shaft, stationary racks engaged by said pinions, a handle on said shaft for rotating the latter and said pinions in unison, a guide 110 member on the bottom of said head and movable in said ways, and a wall on the end of said trough opposite to said slicing devices for limiting the movement of said head and plunger, in combination with 115 means for detaching said plunger from its head.
